(57) **CLAIM**

The ornamental design for a wire stripper, as shown and described.

DESCRIPTION

FIG. 1 is a front view of the wire stripper according to the present invention.

FIG. 2 is a rear view of the wire stripper of FIG. 1.

FIG. 3 is a left side view of the wire stripper of FIG. 1.

FIG. 4 is a right side view of the wire stripper of FIG. 1.

FIG. 5 is a top view of the wire stripper of FIG. 1.

FIG. 6 is a bottom view of the wire stripper of FIG. 1.

FIG. 7 is a first perspective view of the wire stripper of FIG. 1; and,

FIG. 8 is a second perspective view of the wire stripper of FIG. 1.

1 Claim, 7 Drawing Sheets
